L. G. Kniffen

UNITED STATES PATENT OFFICE.

LE GRAND KNIFFEN, OF WORCESTER, MASSACHUSETTS.

IMPROVED REFRIGERATOR-CAR.

Specification forming part of Letters Patent No. 69,223, dated September 24, 1867.

To all whom it may concern:

Be it known that I, LE GRAND KNIFFEN, of the city and county of Worcester, in the State of Massachusetts, have invented a new and useful Refrigerator-Car for transporting and preserving dressed meats and other perishable articles, of which the following is a full, clear, and exact description, reference being had to the accompanying drawings, which make part of this specification, and in which—

Figure 1 represents a view in perspective of the body of an ordinary freight-car to which my invention has been adapted. Fig. 2 represents a longitudinal vertical section, and Fig. 3 a vertical transverse section through the same.

It is the object of my invention to produce a refrigerator-car in which fresh meats and other perishable articles can safely be transported to distant markets; and to this end the invention herein claimed consists, first, in a car lined with a material which is a bad conductor of heat, and containing a refrigerating apparatus or material to maintain a low temperature; second, in lining an ordinary box freight-car with some fibrous or textile material which will resist the transmission of heat; third, in converting an ordinary freight-car into a refrigerator by lining it with successive layers of paper; fourth, in lining a box-car with removable sections of non-conducting materials; fifth, in lining a refrigerator-car with a yielding or elastic material which is also a bad conductor of heat; sixth, in arranging both the articles to be transported and the refrigerating material within the same non-conducting lining or envelope; seventh, in arranging a hinged door in the lining opposite the doors of the car; eighth, in so arranging removable ice-racks that they will be supported by the sections nearest the door; ninth, in combining with a refrigerator-car a removable ice-rack; tenth, in combining with a refrigerator-car a refrigerating apparatus for producing cold without the use of ice; eleventh, in placing quicklime or other absorbent of moisture within the car to produce a dry atmosphere; twelfth, in arranging props around the car to support a series of top beams, which can be moved toward or from each other to accommodate different-sized carcasses to be suspended from them;

thirteenth, in arranging movable swiveling hooks on the cross-beams.

In the accompanying drawings, which show one convenient mode of carrying out my invention, an ordinary freight box-car, A, which may be constructed either of wood or iron, is shown as lined with a fibrous or textile material, B, which is a bad conductor of heat. This lining, in this instance, is composed of several thicknesses of pasteboard covered at their edges or places of abutment with woolen or felt cloth, more effectually to exclude the air, and forming sections made to fit the interior of the car, and united by hooks C and staples on the inside of the car, or some other fastening which will permit them readily to be separated. The lining may be glazed or varnished, if desired, to resist moisture and prevent it from acquiring the odor of the articles transported. The floor-sections are first laid down and the side sections erected upon them. The end sections are arranged between the side sections, and these latter are provided with props D, upon which cross-beams E rest. These beams not only keep the side sections in place, but are laid loosely on the props, so that the distance between them may be varied. Swiveling flesh-hooks i are suspended from these beams by rectangular hooks I, which embrace the sides and top of the beams and can be moved endwise on it. As the distance between the beams can be varied by sliding them on their props or stringers, and as the hooks can be moved toward or from each other on their beams, it will be seen that they can readily be adapted to the conveyance of carcasses of different sizes. The top sections rest upon the side sections and on top the beam E. In the section which would come opposite each door of the car I make a door, I, which I prefer to open outward on hinges, as this arrangement is less complicated and more convenient than a sliding door in the lining would be. Racks F are arranged on the inner side of each door-section to receive cross-bars to support the ice to cool the car. The ice may be placed within a box or vessel, and wrapped in or covered with woolen cloths, sawdust, or other bad conductors of heat, to prevent it melting too fast. A dripping pan and pipe should also be provided to receive

and discharge the water which flows from the melting ice.

By the above-described mode of construction the articles to be transported can be first arranged within the car and the ice then put in, and in cold weather the rack may be removed and its place occupied by freight. To render the car dry as well as cold, I place unslaked lime, or some other absorbent of moisture, in vessels in any convenient position in the car. I also, under some circumstances, use refrigerating-mixtures to cool the car without the use of ice. This might be done by pipes arranged along the top of the car to receive the mixture and let the warm air, which naturally rises, surround the pipes. In the present instance, however, I have shown globular vessels arranged at each end of the car and supplied with pipes G passing through the top to receive a mixture of Glauber salts and sulphuric acid, or some other mixture, which, by its rapid evaporation, will produce intense cold.

What I claim as my invention, and desire to secure by Letters Patent, is—

1. A refrigerator-car constructed substantially in the manner described, for the purpose of transporting meats and other perishable articles.

2. Lining an ordinary box-car with fibrous or textile non conducting material, for the purpose set forth.

3. Converting an ordinary freight-car into a refrigerator by lining it with successive sheets or layers of thick paper, substantially in the manner described.

4. The combination, substantially in the manner described, with a box-car, of removable sections or linings of non-conducting material, whereby I can in a few moments convert an ordinary car into a refrigerator.

5. Lining a box-car with elastic non-conducting material which will yield to the working of the car, or even allow it to be broken without rupturing the non-conducting envelope.

6. The arrangement, in a refrigerator-car, of both the articles to be kept cool and the ice or refrigerating apparatus inside the non-conducting envelope, whereby I protect the refrigerating apparatus from the external heat without additional protection.

7. The arrangement, as described, of the hinged door in the lining with the sliding door of the car, whereby direct access can be had to the refrigerating-chamber.

8. The arrangement, as described, of removable ice-racks with the lining sections nearest the doors, (or those in which the doors are placed,) whereby the ice is placed in last, and is thus more convenient of access and space economized.

9. In combination with a refrigerator-car, a removable ice-rack, which can be taken out when not required and its room occupied by other things.

10. The arrangement, in a refrigerator-car, of a refrigerating apparatus to produce cold without using ice when desired.

11. The arrangement, within a refrigerator-car, of quicklime or other absorbent of moisture, to maintain a dry as well as a cold atmosphere.

12. The arrangement, as described, of the removable side props and top beams, whereby the sections are held in place, and the distance between the beams can be varied to suit carcasses of different sizes.

13. The arrangement, as described, on the top or cross-beams, of the sliding swiveling hooks, whereby the spaces between the hooks can be varied and the carcasses conveniently swung.

In testimony whereof I have hereunto subscribed my name.

L. G. KNIFFEN.
